United States Patent Office

Des. 218,718
Patented Sept. 15, 1970

218,718

SAILBOAT

Carter Pyle, 1421 Front St., Lahaina, Hawaii 96761,
and Joe Quigg, 4797 Farmer Road, Honolulu, Hawaii
96761

Filed Apr. 1, 1969, Ser. No. 16,542

Term of patent 14 years

Int. Cl. D12—06

U.S. Cl. D71—1

FIG. 1

FIG. 2

FIG. 3

FIG. 4

FIG. 5

FIG. 1 is a side elevational view of a sailboat showing our new design;

FIG. 2 is a side elevational view of the side opposite that shown in FIG. 1 with the spars and sail deleted for convenience of illustration;

FIG. 3 is a top plan view of said sailboat;

FIG. 4 is a rear elevational view of said sailboat; and

FIG. 5 is a front elevational view of said sailboat.

We claim:

The ornamental design for a sailboat, substantially as shown and described.
